US0D1048452S

(12) **United States Design Patent** (10) **Patent No.:** **US D1,048,452 S**
(45) **Date of Patent:** **** Oct. 22, 2024**

(54) **MASSAGE APPARATUS**

(71) Applicant: **SHENZHEN MOZA TECHNOLOGY CO., LIMITED**, Shenzhen (CN)

(72) Inventor: **Yinghua Lai**, Shenzhen (CN)

(73) Assignee: **SHENZHEN MOZA TECHNOLOGY CO., LIMITED**, Shenzhen (CN)

(**) Term: **15 Years**

(21) Appl. No.: **35/516,448**

(22) Filed: **Nov. 25, 2022**

(80) **Hague Agreement Data**

Int. Filing Date: **Nov. 25, 2022**

Int. Reg. No.: **DM/225885**

Int. Reg. Date: **Nov. 25, 2022**

Int. Reg. Pub. Date: **Mar. 3, 2023**

Assistant Examiner — Landon Thomas Cassell

(57) **CLAIM**

The ornamental design for a massage apparatus as shown and described.

DESCRIPTION

1.1 is a front, right, and top perspective view of a massage apparatus showing our new design;

1.2 is a back, left, and bottom perspective view thereof;

1.3 is a front view thereof;

1.4 is a back view thereof;

1.5 is a left side elevation view thereof;

1.6 is a right side elevation view thereof;

1.7 is a top plan view thereof;

1.8 is a bottom view thereof; and

1.9 is a back, left, and bottom perspective view showing the massage apparatus in a position of folded state use.

1 Claim, 9 Drawing Sheets
